ALFRED W. MELLOWES, OF MILWAUKEE, WISCONSIN, ASSIGNOR OF ONE-HALF TO
EDWIN B. H. TOWER, JR., OF MILWAUKEE, WISCONSIN

AIR COOLING AND WATER FREEZING EVAPORATOR FOR MECHANICAL REFRIGERATING APPARATUS

Application filed February 26, 1931, Serial No. 448,412. Renewed June 20, 1937.

The invention relates to an air cooling and water freezing evaporator for mechanical refrigerating apparatus.

The evaporator to which the invention applies in particular is of the type employed in a domestic refrigerator to freeze water in a freezing compartment and cool air in a cooling compartment.

The mechanical refrigerating apparatus of which the evaporator forms a part is provided with a condenser to supply liquid refrigerant to the evaporator and a compressor driven by an electric motor to withdraw vaporized refrigerant from the evaporator and deliver it to the condenser to be liquefied therein.

The invention has as its object to provide an evaporator which will create a freezing temperature in the freezing compartment and a cooling temperature above freezing temperature in the cooling compartment.

Another object is to provide an evaporator which will maintain a wide difference between the freezing temperature in the freezing compartment and the cooling temperature in the cooling compartment.

Another object is to provide an evaporator which will freeze water and cool air at a rapid rate under wide variations in temperature that the conditions in service tend to create in the cooling compartment.

Another object is to provide an evaporator which is simple and compact and which will occupy a small space in the cooling compartment.

Another object is to provide an evaporator which will shorten the time the compressor is in operation and lessen the electrical power consumed by the electric motor.

Another object is to provide an evaporator which will increase the efficiency of the mechanical refrigerating apparatus in which it is employed.

Another object is to provide an evaporator which will lessen the size and capacity of the compressor required for a given capacity in the evaporator.

Another object is to provide an evaporator which will not require a compressor with excess capacity to compress superheated refrigerant.

According to the invention as it is ordinarily embodied in practice, the evaporator is provided with multiple refrigerant tubes arranged to provide multiple freezing tubes upon both lateral sides of a freezing space or compartment to create a freezing temperature therein and multiple exposed cooling tubes in a cooling space or compartment to cool ambient air therein to a cooling temperature above freezing temperature by direct contact therewith.

The evaporator which is illustrated in the accompanying drawings exemplifies and embodies the invention, and the views therein are as follows:

Fig. 1 is a front view of the evaporator with parts thereof in section.

Fig. 2 is a side view of the same evaporator.

Fig. 3 is a front view of a modified evaporator.

Fig. 4 is a side view of the modified evaporator, with the brine tank shown in section on the line 4-4 of Figure 3.

Figures 1 and 2

The refrigerator in which the evaporator is employed is provided with a cooling or refrigerating compartment in which the evaporator is arranged to cool the air therein to a cooling temperature above freezing temperature.

The cooling or refrigerating compartment may be divided into an evaporator compartment and a food compartment by a partition 2 which is provided with an inlet passage 3 to admit at the top of the evaporator compartment warm air from the food compartment and an outlet passage 4 to discharge at the bottom of the evaporator compartment cooled air into the food compartment.

The evaporator is formed in general by multiple refrigerant tubes 5 which are arranged in two opposite groups and connected at the lower end in multiple to a refrigerant supply header or manifold 6 and at the upper end in multiple to a refrigerant discharge header or manifold 7.

The multiple refrigerant tubes form at the lower part thereof multiple freezing tubes

8 arranged upon both lateral sides of a freezing space and at the upper part thereof multiple cooling tubes 9 exposed to direct contact with the ambient air in a cooling space 5 within the cooling or refrigerating compartment.

The freezing space has arranged therein a freezing compartment 10 which may have two chambers, each of which is open at its 10 front end to receive endwise a removable ice tray or drawer 11.

The freezing compartment and freezing tubes may be enclosed within a tank 12 which contains brine or other suitable liquid to 15 increase the thermal conductivity between the freezing tubes and the freezing compartment.

The tank is attached to the freezing tubes and carries the freezing compartment, but 20 the freezing compartment may be supported in various other ways.

The air cooling tubes may be reflexed above the freezing compartment to increase the heat absorbing surface thereof within a given 25 space.

The evaporator is supplied with liquid refrigerant from a condenser through a pipe 13 connected to the refrigerant supply manifold, and vaporized refrigerant is returned 30 therefrom to a compressor through a pipe 14 connected to the refrigerant discharge manifold.

The cooling temperature which the evaporator creates in the cooling or refrigerating compartment may be regulated by a thermostat 15 which controls a pressure switch or other instrumentality to start the motor upon the cooling temperature increasing to about forty-two degrees Fahrenheit (42° F.) 35 and to stop the motor upon the cooling temperature decreasing to about thirty-eight degrees Fahrenheit (38° F.).

When the evaporator is in service, the refrigerant tubes are filled with liquid refrigerant to such a level that liquid refrigerant is always available in the cooling tubes to absorb sufficient heat from the cooling compartment to create a cooling temperature 45 therein.

50 The freezing tubes will create a freezing temperature, about twenty degrees Fahrenheit (20° F.) in the freezing compartment and the cooling tubes will create a cooling temperature, about forty degrees Fahrenheit (40° F.) in the cooling compartment, even though the temperature outside the refrigerator varies through a wide range and thereby varies the heat required to be absorbed from the cooling compartment.

55 As the freezing compartment has multiple freezing tubes upon both lateral sides thereof to absorb heat therefrom from end to end, the water therein is frozen at a rapid rate.

60 As the cooling tubes are exposed to direct

contact with the ascended warm air in proximity thereto, the cooling compartment is cooled at a rapid rate to a cooling temperature.

Accordingly, the motor is in operation a 70 shorter time and less electrical power is consumed.

As the evaporator returns to the compressor saturated and not superheated vaporized refrigerant, the compressor and the motor may have a smaller size and capacity 75 for a given capacity in the evaporator.

As the cooling tubes cool the ascended warm air in proximity thereto and cooled air descends therefrom, the freezing tubes 80 and the freezing compartment are shielded from the warm air by the cooling tubes and enveloped in descending cooled air.

The evaporator has arranged upon the front thereof a removable front plate 16 fastened thereto by screws 17, and the front plate has an entrance into each chamber in the freezing compartment.

The ice tray has arranged upon the front thereof a cover plate 18 from which extends 90 a handle 19 and the cover plate and the ice tray are spaced from each other to provide a passage therebetween.

When the ice tray is in its chamber in the freezing compartment, the entrance therefor 95 through the front plate is closed by the cover plate.

Figures 3 and 4

The modified evaporator differs from the 100 evaporator that has already been described merely in that the cooling tubes have a different conformation and an oil separator forms the refrigerant discharge header or manifold.

The invention which is embodied in the oil separator is the subject of a separate application.

The oil separator is provided with a reservoir 20 having a depending trough 21, and the refrigerant tubes are connected to the reservoir and communicate therewith above the liquid level therein.

The refrigerant discharge pipe 14 extends upward through the trough and communicates with the reservoir below the refrigerant tubes.

The trough is connected to a refrigerant supply tube by an overflow pipe 22 which communicates with the refrigerant tube below the refrigerant discharge pipe 14.

The liquid refrigerant delivered to the refrigerant tubes has commingled therewith oil from the compressor.

When the liquid refrigerant in the refrigerant tubes is being vaporized, its ebullition causes liquid refrigerant and oil to pass into the separator reservoir and accumulate in the trough.

When the oil rises and accumulates upon 130

the liquid refrigerant in the trough, it overflows into the refrigerant discharge pipe which conducts it back to the compressor.

5 The liquid refrigerant in the trough is kept from overflowing into the refrigerant discharge pipe by the overflow pipe 22 which returns it to the refrigerant tubes.

10 The invention exemplified by the evaporators described herein may be embodied in various different forms which will be within the purview of the hereinafter claims.

15 The invention claimed is:

1. An air cooling and water freezing mechanical refrigerating evaporator, comprising refrigerant containing means arranged opposite to each other in a horizontal relation and exposed to direct contact with the ambient air at the upper part thereof, a water freezing compartment arranged between said means below said upper part thereof, and means to deliver vaporizable refrigerant to the aforesaid means in multiple.

2. An air cooling and water freezing mechanical refrigerating evaporator, comprising refrigerant containing means surrounding a water freezing compartment and exposed to direct contact with the ambient air outside said water freezing compartment, and means to deliver vaporizable refrigerant to opposite sides of the aforesaid means in multiple.

3. An air cooling and water freezing mechanical refrigerating evaporator, comprising a refrigerant supply manifold, a water freezing compartment, and independent refrigerant tubes arranged on each side of said compartment connected to said refrigerant supply manifold in multiple and exposed to direct contact with the ambient air outside said compartment.

4. An air cooling and water freezing mechanical refrigerating evaporator, comprising a refrigerant supply manifold, a water freezing compartment, and independent refrigerant tubes arranged on each side of said compartment connected to said refrigerant supply manifold in multiple and having the upper parts thereof exposed to direct contact with the ambient air.

5. An air cooling and water freezing mechanical refrigerating evaporator, comprising a refrigerant supply manifold, a water freezing compartment, and independent reflexed refrigerant tubes embracing said compartment connected to said refrigerant supply manifold in multiple and exposed to direct contact with the ambient air outside said compartment.

6. An air cooling and water freezing mechanical refrigerating evaporator, comprising a refrigerant supply manifold, a water freezing compartment, and independent reflexed refrigerant tubes embracing said compartment connected to said refrigerant supply manifold in multiple and having the up-

per parts thereof exposed to direct contact with the ambient air.

7. An air cooling and water freezing mechanical refrigerating evaporator arranged within a refrigerating compartment, comprising a refrigerant supply manifold, a water freezing compartment, and independent reflexed refrigerant tubes embracing said compartment connected to said refrigerant supply manifold in multiple and exposed to direct contact with the ambient air outside said freezing compartment to cause cooled air to envelop said compartment.

8. An air cooling and water freezing mechanical refrigerating evaporator arranged within a refrigerating compartment and embracing a water freezing compartment, comprising a refrigerant container having independent refrigerant ducts arranged upon opposite sides of said freezing compartment and exposed to direct contact with the ambient air outside said freezing compartment, and means connected to said container to deliver refrigerant to said ducts in multiple.

9. An air cooling and water freezing mechanical refrigerating evaporator, comprising a refrigerant container arranged within a refrigerating compartment and embracing a water freezing compartment, an inner wall upon said container in direct contact throughout a substantial area with the refrigerant to absorb heat outward from said freezing compartment on both lateral sides thereof, an outer wall upon said container exposed to direct contact throughout a substantial area with the refrigerant and the ambient air above said freezing compartment, and means connected to said refrigerant container to deliver refrigerant to opposite sides thereof in multiple.

10. An air cooling and water freezing evaporator, comprising a liquid refrigerant container providing in part a freezing container arranged upon each of opposite lateral sides of a freezing compartment to absorb heat from end to end thereof at a rapid rate to create a freezing temperature therein and in part a cooling container exposed to direct contact with the air in a cooling compartment to absorb heat therefrom at a rapid rate to create a cooling temperature therein and cause cooled air to envelope said freezing containers and said freezing compartment, and means connecting the refrigerant containers on opposite sides of said freezing compartment in multiple to a refrigerant supply inlet and a refrigerant discharge outlet.

11. The combination with a refrigerating compartment of an evaporator arranged therein and comprising a tubular header for receiving refrigerant, independent parallel tubes connected to opposite sides of said header and arranged to provide a low temperature zone between the same and extended

- beyond said zone into the path of the circulating air in said compartment to cool the same and create a blanket of cooled air around said low temperature zone.
12. An air cooling and water freezing evaporator, comprising freezing means arranged upon both lateral sides of a freezing space to create a freezing temperature therein, cooling means having independent multiple exposed tubes arranged outward from the aforesaid freezing means in a cooling space to cool circulating air therein to a cooling temperature above freezing temperature by direct contact therewith, and means connecting both the aforesaid means to a refrigerant supply inlet and a vapor refrigerant outlet. 70
13. An air cooling and water freezing evaporator, comprising freezing means arranged upon both lateral sides of a freezing space to create a freezing temperature therein, cooling means having independent multiple exposed tubes arranged outward from the aforesaid freezing means in a cooling space to cool circulating air therein to a cooling temperature above freezing temperature by direct contact therewith, a freezing compartment arranged within said freezing space to receive a removable ice tray, a cooling compartment enclosing said cooling space, and means connecting both the aforesaid means to a refrigerant supply inlet and a vapor refrigerant outlet. 75
14. An air cooling and water freezing evaporator comprising freezing means arranged upon both lateral sides of a freezing space to create a freezing temperature therein, cooling means having independent multiple exposed tubes arranged outward from the aforesaid freezing means in a cooling space to cool circulating air therein to a cooling temperature above freezing temperature by direct contact therewith, a freezing compartment arranged within said freezing space to receive a removable ice tray, a heat conductor having higher thermal conductivity than air to transfer heat from said freezing compartment to said freezing means, and means connecting both the aforesaid means to a refrigerant supply inlet and a vapor refrigerant outlet. 80
15. An air cooling and water freezing evaporator, comprising freezing means arranged upon both lateral sides of a freezing space to create a freezing temperature therein, cooling means having independent multiple exposed tubes arranged outward from the aforesaid freezing means in a cooling space to cool circulating air therein to a cooling temperature above freezing temperature by direct contact therewith, and means connecting said freezing means from warm circulating air by causing cooled air to envelop said freezing space and said freezing means, a freezing compartment arranged within said freezing space to receive a removable ice tray, a cooling compartment enclosing said cooling space, and means connecting both the aforesaid means to a refrigerant supply inlet and a vapor refrigerant outlet. 85
16. An air cooling and water freezing evaporator, comprising freezing means arranged upon both lateral sides of a freezing space to create a freezing temperature therein, cooling means having independent multiple exposed tubes arranged outward from the aforesaid freezing means in a cooling space to cool circulating air therein to a cooling temperature above freezing temperature by direct contact therewith and to shield said freezing space and said freezing means from warm circulating air by causing cooled air to envelop said freezing space and said freezing means, a freezing compartment arranged within said freezing space to receive a removable ice tray, a cooling compartment enclosing said cooling space, and means connecting both the aforesaid means to a refrigerant supply inlet and a vapor refrigerant outlet. 90
17. An air cooling and water freezing evaporator, comprising freezing means arranged upon both lateral sides of a freezing space to create a freezing temperature therein, cooling means having independent multiple exposed tubes arranged outward from the aforesaid freezing means in a cooling space to cool circulating air therein to a cooling temperature above freezing temperature by direct contact therewith and to shield said freezing space and said freezing means from warm circulating air by causing cooled air to envelop said freezing space and said freezing means, a freezing compartment arranged within said freezing space to receive a removable ice tray, a heat conductor having higher thermal conductivity than air to transfer heat from said freezing compartment to said freezing means, and means connecting both the aforesaid means to a refrigerant supply inlet and a vapor refrigerant outlet. 95
18. An air cooling and water freezing evaporator, comprising independent multiple tubes arranged to provide multiple freezing tubes upon both lateral sides of a freezing space to create a freezing temperature therein and multiple exposed cooling tubes arranged outward from said freezing tubes in a cooling space to cool circulating air therein to a cooling temperature above freezing temperature by direct contact therewith, and means connecting said multiple tubes to a refrigerant supply inlet and a vapor refrigerant outlet. 100
19. An air cooling and water freezing evaporator, comprising independent multiple tubes arranged to provide multiple freezing tubes upon both lateral sides of a freezing space to create a freezing temperature therein and multiple exposed cooling tubes arranged outward from said freezing tubes in a cooling space to cool circulating air 105
20. An air cooling and water freezing evaporator, comprising independent multiple tubes arranged to provide multiple freezing tubes upon both lateral sides of a freezing space to create a freezing temperature therein and multiple exposed cooling tubes arranged outward from said freezing tubes in a cooling space to cool circulating air 110
21. An air cooling and water freezing evaporator, comprising independent multiple tubes arranged to provide multiple freezing tubes upon both lateral sides of a freezing space to create a freezing temperature therein and multiple exposed cooling tubes arranged outward from said freezing tubes in a cooling space to cool circulating air 115
22. An air cooling and water freezing evaporator, comprising independent multiple tubes arranged to provide multiple freezing tubes upon both lateral sides of a freezing space to create a freezing temperature therein and multiple exposed cooling tubes arranged outward from said freezing tubes in a cooling space to cool circulating air 120
23. An air cooling and water freezing evaporator, comprising independent multiple tubes arranged to provide multiple freezing tubes upon both lateral sides of a freezing space to create a freezing temperature therein and multiple exposed cooling tubes arranged outward from said freezing tubes in a cooling space to cool circulating air 125
24. An air cooling and water freezing evaporator, comprising independent multiple tubes arranged to provide multiple freezing tubes upon both lateral sides of a freezing space to create a freezing temperature therein and multiple exposed cooling tubes arranged outward from said freezing tubes in a cooling space to cool circulating air 130

therein to a cooling temperature above freezing temperature by direct contact therewith, a freezing compartment arranged within said freezing space to receive a removable ice tray, a cooling compartment enclosing said cooling space, and means connecting said multiple tubes to a refrigerant supply inlet and a vapor refrigerant outlet.

20. An air cooling and water freezing
10 evaporator, comprising independent multi-
ple tubes arranged to provide multiple freez-
ing tubes upon both lateral sides of a freez-
ing space to create a freezing temperature
therein and multiple exposed cooling tubes
15 arranged outward from said freezing tubes
in a cooling space to cool circulating air
therein to a cooling temperature above freez-
ing temperature by direct contact therewith,
a freezing compartment arranged within
20 said freezing space to receive a removable ice
tray, a heat conductor having higher thermal
conductivity than air to transfer heat from
said freezing compartment to said freezing
tubes, and means connecting said multiple
25 tubes to a refrigerant supply inlet and a
vapor refrigerant outlet.

21. An air cooling and water freezing evaporator, comprising independent multiple tubes arranged to provide multiple freezing tubes upon both lateral sides of a freezing space to create a freezing temperature therein and multiple exposed cooling tubes arranged outward from said freezing tubes in a cooling space to cool circulating air therein to a cooling temperature above freezing temperature by direct contact therewith and to shield said freezing space and said freezing tubes from warm circulating air by causing cooled air to envelop said freezing space and freezing tubes, and means connecting said multiple tubes to a refrigerant supply inlet and a vapor refrigerant outlet.

22. An air cooling and water freezing evaporator, comprising independent multiple tubes arranged to provide multiple freezing tubes upon both lateral sides of a freezing space to create a freezing temperature therein and multiple exposed cooling tubes arranged outward from said freezing tubes 45 in a cooling space to cool circulating air therein to a cooling temperature above freezing temperature by direct contact therewith and to shield said freezing space and said freezing tubes from warm circulating air by 50 causing cooled air to envelop said freezing space and freezing tubes, a freezing compartment arranged within said freezing space to receive a removable ice tray, a cooling compartment enclosing said cooling space, and 55 means connecting said multiple tubes to a refrigerant supply inlet and a vapor refrigerant outlet. 60

23. An air cooling and water freezing evaporator, comprising independent multiple tubes arranged to provide multiple freezing

tubes upon both lateral sides of a freezing space to create a freezing temperature therein and multiple exposed cooling tubes arranged outward from said freezing tubes in a cooling space to cool circulating air therein to a cooling temperature above freezing temperature by direct contact therewith and to shield said freezing space and said freezing tubes from warm circulating air by causing cooled air to envelop said freezing space and freezing tubes, a freezing compartment arranged within said freezing space to receive a removable ice tray, a heat conductor having higher thermal conductivity than air to transfer heat from said freezing compartment to said freezing tubes, and means connecting said multiple tubes to a refrigerant supply inlet and a vapor refrigerant outlet.

24. An air cooling and water freezing evaporator, comprising reflexed multiple tubes arranged to provide multiple freezing tubes upon both lateral sides of a freezing space to create a freezing temperature therein and multiple exposed cooling tubes arranged outward from said freezing tubes in a cooling space to cool circulating air therein to a cooling temperature above freezing temperature by direct contact therewith and to shield said freezing space and said freezing tubes from warm circulating air by causing cooled air to envelop said freezing space and freezing tubes, and means connecting said multiple tubes to a refrigerant supply inlet and a vapor refrigerant outlet. 85 90 95

25. An air cooling and water freezing evaporator, comprising reflexed multiple tubes arranged to provide multiple freezing tubes upon both lateral sides of a freezing space to create a freezing temperature therein and multiple exposed cooling tubes arranged outward from said freezing tubes in a cooling space to cool circulating air therein to a cooling temperature above freezing temperature by direct contact therewith and to shield said freezing space and said freezing tubes from warm circulating air by causing cooled air to envelop said freezing space and freezing tubes, a freezing compartment arranged within said freezing space to receive a removable ice tray, a cooling compartment enclosing said cooling space, and means connecting said multiple tubes to a refrigerant supply inlet and a vapor refrigerant outlet. 100
105
110
115

26. An air cooling and water freezing evaporator, comprising a liquid refrigerant supply header, multiple tubes connected to said header to receive liquid refrigerant therefrom independent of each other and arranged to provide multiple freezing tubes upon both lateral sides of a freezing space to create a freezing temperature therein and multiple exposed cooling tubes arranged outward from said freezing tubes in a cooling space to cool circulating air therein to a 130

cooling temperature above freezing temperature by direct contact therewith.

27. An air cooling and water freezing evaporator, comprising a liquid refrigerant supply header, multiple tubes connected to said header to receive liquid refrigerant therefrom independent of each other and arranged to provide multiple freezing tubes upon both lateral sides of a freezing space 10 to create a freezing temperature therein and multiple exposed cooling tubes arranged outward from said freezing tubes in a cooling space to cool circulating air therein to a cooling temperature above freezing temperature 15 by direct contact therewith, a freezing compartment arranged within said freezing space to receive a removable ice tray, and a cooling compartment enclosing said cooling space.

28. An air cooling and water freezing evaporator, comprising a liquid refrigerant supply header, multiple tubes connected to said header to receive liquid refrigerant therefrom independent of each other and arranged to provide multiple freezing tubes 25 upon both lateral sides of a freezing space to create a freezing temperature therein and multiple exposed cooling tubes arranged outward from said freezing tubes in a cooling space to cool circulating air therein to a 30 cooling temperature above freezing temperature by direct contact therewith, a freezing compartment arranged within said freezing space to receive a removable ice tray, and a heat conductor having higher thermal conductivity 35 than air to transfer heat from said freezing compartment to said freezing tubes.

29. An air cooling and water freezing evaporator, comprising a liquid refrigerant supply header, independent multiple tubes 40 connected to said header to receive liquid refrigerant therefrom independent of each other and arranged to provide multiple freezing tubes upon both lateral sides of a freezing space to create a freezing temperature there- 45 in and multiple exposed cooling tubes arranged outward from said freezing tubes in a cooling space to cool circulating air therein to a cooling temperature above freezing temperature by direct contact therewith and 50 to shield freezing space and said freezing tubes from warm circulating air by causing cooled air to envelop said freezing space and said freezing tubes.

30. An air cooling and water freezing evaporator, comprising a liquid refrigerant supply header, independent multiple tubes 55 connected to receive liquid refrigerant therefrom independent of each other and arranged to provide multiple freezing tubes upon both 60 lateral sides of a freezing space to create a freezing temperature therein and multiple exposed cooling tubes arranged outward from said freezing tubes in a cooling space to cool circulating air therein to a cooling 65 temperature above freezing temperature by

direct contact therewith and to shield said freezing space and said freezing tubes from warm circulating air by causing cooled air to envelop said freezing space and said freezing tubes, a freezing compartment arranged within said freezing space to receive a removable ice tray, and a cooling compartment enclosing said cooling space.

31. An air cooling and water freezing evaporator, comprising a liquid refrigerant supply header, independent multiple tubes connected to said header to receive liquid refrigerant therefrom independent of each other and arranged to provide multiple freezing tubes upon both lateral sides of a freezing space to create a freezing temperature therein and multiple exposed cooling tubes arranged outward from said freezing tubes in a cooling space to cool circulating air therein to a cooling temperature above freezing temperature by direct contact therewith and to shield said freezing space and said freezing tubes from warm circulating air by causing cooled air to envelop said freezing space and said freezing tubes, a freezing compartment arranged within said freezing space to receive a removable ice tray, and a cooling compartment enclosing said cooling space.

32. An air cooling and water freezing evaporator, comprising freezing means having multiple freezing tubes arranged upon both lateral sides of a freezing space to create a freezing temperature therein and multiple exposed cooling tubes arranged outward from said freezing space to cool air in a cooling space outside said freezing space by direct contact therewith and to shield said freezing space and said freezing means from warm circulating air.

33. An air cooling and water freezing evaporator, comprising means to provide multiple ducts arranged to provide in part multiple freezing ducts upon both lateral sides of a freezing space to create a freezing temperature therein and in part multiple exposed cooling ducts having direct contact with the circulating air in a cooling space outside said freezing space and arranged outward from said freezing ducts to shield said freezing space and said freezing ducts from warm circulating air, a freezing compartment arranged within said freezing space to receive a removable ice tray, and a cooling compartment enclosing said cooling space.

34. An air cooling and water freezing evaporator, comprising multiple tubes arranged to provide in part multiple freezing tubes upon both lateral sides of a freezing space to create a freezing temperature therein and in part multiple exposed cooling tubes having direct contact with the circulating air in a cooling space outside said freezing space and arranged outward from said freezing

tubes to shield said freezing space and said freezing tubes from warm circulating air, a freezing compartment arranged within said freezing space to receive a removable ice tray, and a cooling compartment enclosing said cooling space.

35. A mechanical refrigerating evaporator comprising a refrigerant container, a freezing compartment embraced by said refrigerant container and having an open front end, a front plate having an entrance therethrough to said compartment, an ice tray arranged within said compartment, a cover plate connected to said ice tray to engage said front plate and close said entrance and spaced from the front of said ice tray to provide a passage between said cover plate and said ice tray, and a handle arranged upon the front of said cover plate.

20 36. A mechanical refrigerating evaporator comprising a refrigerant container, a freezing compartment embraced by said refrigerant container and having an open front end, a removable front plate having an entrance therethrough to said compartment, an ice tray arranged within said compartment, a cover plate connected to said ice tray to engage said front plate and close said entrance and spaced from the front of said ice tray to provide a passage between said cover plate and said ice tray, and a handle arranged upon the front of said cover plate.

35 37. A mechanical refrigerating evaporator comprising a refrigerant container, a freezing compartment embraced by said refrigerant container and having an open front end, a removable front plate carried by said evaporator and having an entrance therethrough to said compartment, an ice tray arranged within said compartment, a cover plate connected to said ice tray to engage said front plate and close said entrance and spaced from the front of said ice tray to provide a passage between said cover plate and said ice tray, and a handle arranged upon the front of said cover plate.

40 In witness whereof, I have hereunto subscribed my name.

ALFRED W. MELLOWES.

CERTIFICATE OF CORRECTION.

Patent No. 1,833,846.

Granted November 24, 1931, to

ALFRED W. MELLOWES.

It is hereby certified that error appears in the printed specification of the above numbered patent requiring correction as follows: Page 1, line 77, after "refrigerator" insert the numeral 1; page 5, line 12, claim 20, for the syllable "inb" read ing; page 6, line 50, claim 29, after "shield" insert said, and line 57, claim 30, after "to" insert said header to; and that the said Letters Patent should be read with these corrections therein that the same may conform to the record of the case in the Patent Office.
